UNITED STATES PATENT OFFICE.

DAVID A. McDONALD, OF CHICAGO, ILLINOIS.

MOUTHPIECE FOR CORNETS AND THE LIKE.

1,166,137.

Specification of Letters Patent. Patented Dec. 28, 1915.

Application filed July 30, 1914. Serial No. 854,000.

To all whom it may concern:

Be it known that I, DAVID A. McDONALD, a citizen of the United States, and a resident of the city of Chicago, county of Cook, and State of Illinois, have invented certain new and useful Improvements in Mouthpieces for Cornets and the like, of which the following is a specification.

My invention relates to improvements in mouth pieces for cornets and similar musical instruments, and has for its object the provision of a mouth piece of this character so shaped as to facilitate the production of clear and pure tones without undue straining of the lips.

The invention consists in the combinations and arrangements of parts hereinafter described and claimed.

The invention will be best understood by reference to the accompanying drawing forming a part of this specification, and in which—

Figure 1 is a longitudinal section taken through a mouth piece embodying my invention, the position of use being indicated in dotted lines, Fig. 2, a front view of the mouth piece, and Fig. 3, a section taken on line 3—3 of Fig. 1.

The preferred form of construction as illustrated in the drawing comprises a mouth piece having a throat 4 of usual construction and a cup 5 provided with a rim adapted to bear against the lips of the player. The upper portion 6 of this rim is curved to conform to a circle 7 of comparatively small radius, and the lower portion 8 of said rim is curved to conform to a circle 9 of comparatively large radius, said portions 6 and 8 being connected smoothly at each side by sharply curved portions 10, said portions 10 being curved to conform with circles of very short radii. The radii of the circles 7 and 9 are substantially in the proportion of one to three. The cup 5 is also curved in transverse section to conform with the curvature of the rim of the mouth piece. This arrangement produces a mouth piece having in general the form of a distorted oval one side of which has a comparatively flat curvature and the other side being arched with respect thereto on a comparatively sharp curve.

It is a well known fact that the tones of cornets and similar wind instruments are produced by vibration of the lips of the player. Under these circumstances in order

to produce clear and pure tones, it is necessary that both lips vibrate synchronously or in unison with each other. Inasmuch as the lips of a person have somewhat different shapes and consistency, it seldom happens that both lips of a player will naturally vibrate synchronously and such synchronous vibration must be obtained either by muscular contraction in one lip or by distorting the position of the mouth piece thereon. This muscular contraction necessarily hardens and stiffens the lip and in this manner many skilful players have been greatly inconvenienced. I have discovered, however, that if the vibration be limited to one of the lips only of the player, this necessity for synchronizing is obviated, the injurious effects thereof avoided and the production of clear and pure tones greatly facilitated. I accomplish this by providing a rim having opposite portions of radically different curvatures, preferably the upper portion of comparatively great curvature and the lower portion of comparatively small curvature, the two being joined together by a sharp curve. By this arrangement a mouth piece may be placed against the lips, as indicated in Fig. 1, and when firmly pressed thereagainst, the lower lip will be held from material vibration while the upper lip will be left free for vibration alone, and at the same time the meeting of the lips be brought opposite the throat of the mouth piece. In this position the only material vibrations will be in the upper lip so that there will be no necessity of synchronizing with the lower lip. In some people the lower lip only will vibrate, or, at least, vibrates much better than the upper lip, in which case the mouth piece may be reversed so as to bring the portion of least curvature against the upper lip. The purity of the tone is also augmented by shaping the cup to conform to the curvature of the rim, as it diminishes in size and approaches the throat of the mouth piece.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A mouth piece provided with a rim in the general form of a distorted oval, one side being of comparatively flat curvature and the other side being arched with respect thereto and more sharply curved, substantially as described.
- 10 2. A mouth piece provided with a rim in the general form of a distorted oval, one side being of comparatively flat curvature and the other side being arched with respect thereto and more sharply curved, said mouth piece being also provided with a throat located adjacent the side having the flatter rim, substantially as described.
- 15 3. A mouth piece in the general form of a distorted oval in transverse section, one side being of comparatively flat curvature and the other side being arched with respect thereto and more sharply curved, substantially as described.
- 20 4. A mouth piece in the general form of

a distorted oval in transverse section, one side being of comparatively flat curvature and the other side being arched with respect thereto and more sharply curved, said mouth piece being also provided with a throat located adjacent the flatter side, substantially as described.

5. A mouth piece in the general form of a distorted oval in transverse section, one side being of comparatively flat curvature and the other side being arched with respect thereto and more sharply curved, said sides being curved on radii in substantially the proportions of one to three, and said mouth piece being also provided with a throat located adjacent the flatter side, substantially as described.

In testimony whereof I have signed my name to this specification in the presence of two subscribing witnesses.

DAVID A. McDONALD.
